Lee W. Parmater and Robert M. Cain, Kalamazoo, Mich.

Application November 7, 1958, Serial No. 53,290

Term of Patent 14 years

(Cl. D52—1)

Figure 1 is a view in perspective of an internal combustion engine tester, showing our new design.

Figure 2 is a front elevational view of the unit of Figure 1.

Figure 3 is a side elevation. This side view corresponds to the visible side of the view of Figure 1; the opposite side is identical.

Figure 4 is a rear elevation view.

Figure 5 is a top view.

Figure 6 is a bottom view.

The dominant features of our design reside in those portions shown in solid lines.

We claim:

The ornamental design for an internal combustion engine tester, as shown and described.
